TRACK GRINDER

Henry J. Perazzoli, Philadelphia, Pa.

Application November 12, 1934, Serial No. 752,750

14 Claims. (Cl. 104—8)

This invention relates to new and useful improvements in railway track grinders and particularly to means for balancing or clamping the grinders with respect to the track rail in a position relative to the surface thereof to be ground.

The principal object of the invention is to provide a device for supporting or clamping a track grinding machine with respect to the track rail and relative to the surface thereof to be ground.

10 A further object of the invention is to provide a device of the general character set forth having novel mechanisms for operating the clamping device to engage the track rail as well as to readily and easily release the same therefrom.

15 A further object of the invention is to provide a device of the character set forth which, while effectively clamping or supporting the grinding machine in position with respect to the surface of the track rail, enables the operator of the 20 grinding machine to move the same longitudinally of the rail to another grinding position without releasing said clamps from the rail.

Other objects and features of the invention and the details of construction thereof are set forth 25 hereinafter and shown in the accompanying drawings, in which:

Fig. 1 is a view in perspective of one end of a track grinder embodying the present invention.

Fig. 2 is an enlarged view in elevation of the 30 clamping device together with the mechanism for operating and controlling the same.

Fig. 3 is a view in section vertically through the disclosure in Fig. 2; and

Fig. 4 is a view similar to the disclosure in 35 Fig. 3 showing the clamping device in engagement with the head of a track rail.

Referring now more particularly to the drawings, reference numerals 1, 1 designate longitudinal side frame members of a track grinder 40 which are respectively connected together at their ends by means of a member 2. A plate 3 is permanently secured to the outer face of the transverse portion of the member 2 by means of bolts 4, and a substantially cylindrical casing 5 45 is disposed vertically with respect to the said plate 3 and permanently secured thereto such as by welding or the like.

As shown in Fig. 3 of the drawings, an annular element 6 is permanently secured transversely of 50 the casing 5 at a point longitudinally thereof approximately midway between the ends of said casing. A rod or shaft 7 is slidably supported within the casing 5 by means of the annular element 6, and a disk 8 is secured to the lower end 55 of said rod or shaft 7 below the annular element

6, and arranged to move with the shaft longitudinally of the casing 5, the said disk 8 being of such diameter that its periphery contacts the inner wall of said casing. The disk 8 is provided with a lateral projecting pin 9 which extends 5 outwardly through a vertical slot 10 formed axially of the casing member 5 adjacent the lower end thereof as shown in Figs. 2 and 3. A second disk 11 similar to the disk 8 is threaded on to the upper end of the rod or shaft 7 and a spring 10 12 is coiled about the latter intermediate the said disk 11 and the fixed annular member 6. Thus it will be seen by referring to Fig. 3 of the drawings that the aforementioned spring 12 is compressible between the annular element 6 and 15 the disk 11, the said spring 12 expanding with respect to the fixed annular stop 6 and functioning to retain the rod or shaft 7 in its uppermost position as shown in Fig. 3 and resist downward movement thereof within the casing 5. 20

In the present instance a pair of substantially L-shaped levers or arms 13 are pivotally connected together in opposed relation by means of a pin 14 approximately at the mid-point of the longer arms thereof, said pivot pin 14 being of sufficient length to permit the same to project through the aforementioned vertical slot 10 in the lower portion of the casing 5 and a substantial distance beyond the outer surface of the latter for a purpose which will later appear. 25 The ends of the longer arms of the levers 13 are each pivotally connected as at 15 to one end of a link 16, the other ends of said links being pivotally connected as at 17 to the disk 8 on the lower end of the shaft 7, and diametrically opposed vertical slots 18 are formed in the lower end portion of the casing 5 to allow for free passage and movement of said levers 13 and links 16 relatively with respect to said casing. 30

Referring particularly to Fig. 4 of the drawings, a cam or roller member 19 is rotatably mounted upon the lower end of each of the levers or arms 13 by means of roller bearings 20 retained in position by means of a washer 21, the said cam or roller member 19 being secured upon 40 the lower end of the arms 13 by means of a nut 22. With reference to the drawings it will be noticed that the lower circumferential portion of the cam or roller members 19 projects outwardly to provide a peripheral shoulder or flange 45 50 51, the purpose for which will be set forth hereinafter.

Referring now particularly to Fig. 2, an arm 23 preferably formed integrally with the casing 5 extends laterally of said casing parallel to the 55

transverse supporting plate 3 previously mentioned, and an actuating arm or lever 24 is pivotally connected at one end to the extremity of said arm 23 by means of a pin 25. A link 26 is 5 pivotally connected at its upper end to the actuating arm or lever 24 at 27, the said link 26 being disposed axially of the casing 5 and connected at its other end to the laterally projecting pin 9 on the disk 8 which is secured to the lower end 10 of the shaft 7. A locking device 28 having a hook portion 29, arranged to engage the previously mentioned pin 14, and a handle or actuating arm 30 is pivotally mounted on the pin 9 to which the lower end of the link 26 is pivotally connected.

15 In the present instance the upper end of the casing 5 is provided with a cap 5a for the purpose of preventing dust and other foreign materials from entering the interior of said casing and a stop 32 is secured diametrically across the bottom end of the casing 5 for the purpose of preventing downward displacement of the shaft and the disk 8 beyond the walls of said casing.

As is customary the grinding machine is supported upon the surface of a track rail 33 having 25 a head 34, by means of a traction wheel 35 mounted upon a shaft 36 and supported in arms 37 which are secured to and depend from the longitudinal side frame members 1, 1 of the machine.

30 In operation of the device with the traction wheels 35 of the machine resting upon the surface of the head 34 of the rail 33, and locking device in engagement with the pin 14, the lever 24 is actuated in the direction of the arrow in Fig. 2, thereby exerting a downward force upon the shaft 7 and moving the same downwardly against the compression force of the spring 12. The lever 24 is actuated downwardly in the above manner until the shaft 7 and the pivotally mounted arms 40 13 suspended therefrom have been lowered sufficiently to enable the rollers 19 on the arms 13 to engage the head of the rail when the handle 30 of the locking device 28 is actuated to disengage the hook portion 29 thereof from engagement with the pin 14. When this locking device has been released from the pin 14 in the aforementioned manner, the relative weight of the cam or roller members 19 at the lower ends of the arms 13 is sufficient to cause said arms 13 to 45 pivot by gravity about said pin 14 toward each other and the track rail and engage the sides of the head thereof as shown in Fig. 4 of the drawings. Of course, when downward pressure upon the actuating arm 24 is released the spring 12 will expand and tend to raise the shaft 7 within 50 the casing 5. The spring 12 will not attain maximum expansion however, since the rollers 19 engaging the rail head will permit the shaft 7 to move upwardly but a small distance into the casing 5, thus leaving sufficient compression in the spring 12 to effectively maintain the grinding machine firmly upon the track rails through engagement of said rails by the cam or roller members 19 previously described.

55 By rotatably mounting the cam or roller members 19 upon the lower ends of the levers 13 in the manner previously described, it is possible to move the grinding machine longitudinally of the track rail 33 from one grinding position to 60 another, without the necessity of continually releasing and reengaging the said cam or roller members 19 with the head 34 of the track rail 33 for each change of position of the machine. As the grinding machine is moved longitudinally of the track rail the clamping effect of the cam roller

19 is not destroyed but the same will merely ride or roll along the sides of the said rail head without the shoulder or lip 31 thereof, becoming disengaged from the underside surfaces thereof.

5 In order to release the rollers 19 from engagement with the rail head 34 the lever 24 is actuated downwardly a sufficient distance to enable the hook 29 of the locking device 28 to engage the pin 14, at which time the arms 13 will have become relatively separated to release the rollers 19 from the head 34 as a result of the continued downward movement of the shaft 7. When the locking device is in engagement with the pin 14 the lever 24 may be released and the clamping device will be elevated to the position shown in Fig. 3 of the drawings by expansion of the spring 12.

10 While a specific embodiment of the invention has been set forth for the purpose of description, it is not intended that the invention be precisely limited thereto but that any changes and modifications may be made without departing from the spirit of the invention where within the scope of the annexed claims.

15 What I claim is:

1. A device for clamping and supporting mobile units upon railway track rails, including arms pivotally connected to each other in opposed relation, means for locking the arms in relatively separated position, said means being releasable to 20 permit the ends of said arms to swing toward each other by gravity, and means operable to lower the arms so that upon upward movement thereof and release of the locking means, said arms will swing toward each other and engage the rail head. 35

2. A device for clamping and supporting mobile units upon railway track rails, including arms pivotally connected to each other in opposed relation, means for locking the arms in relatively separated position, said means being releasable to 40 permit the ends of said arms to swing toward each other by gravity, rollers having a circumferential flange mounted at the lower ends of the arms, means operable to lower said arms so that upon upward movement thereof and release of 45 said locking means the arms will swing toward each other and engage the rollers with the lower side edges of the rail head, and means tending to resist downward movement of said arms.

3. A device for clamping and supporting mobile 50 units upon railway track rails, including a vertically movable rod, means tending to resist movement of said rod, arms pivotally connected to each other and said rod in opposed relation with respect to each other, and means for downwardly 55 actuating the rod to relatively separate the ends of the arms and lower the same so that upon upward movement of said rod the arms will swing toward each other and engage the lower side edges of the rail head. 60

4. A device for clamping and supporting mobile units upon railway track rails, including a vertically movable rod, means tending to resist movement of said rod, arms pivotally connected to each other and the rod in opposed relation with respect to each other, rollers having a circumferential flange mounted at the lower ends of said arms, and means for downwardly actuating the rod to relatively separate the ends of the arms and lower the same so that upon upward movement of the rod the arms will swing toward each other by gravity and engage the rollers with the lower side edges of the rail head. 70

5. A device for clamping and supporting mobile units upon railway track rails, including a verti- 75

cally movable rod, arms pivotally connected to each other and the rod in opposed relation with respect to each other, means for locking the arms in relatively separated position, said means being releasable to permit the ends of said arms to swing toward each other by gravity, and means for downwardly actuating the rod to lower the arms so that upon upward movement of the rod and release of the locking means said arms will 10 swing toward each other and engage the lower side edges of the rail head.

6. A device for clamping and supporting mobile units upon railway track rails, including a vertically movable rod, means tending to resist movement of said rod, arms pivotally connected to each other and the rod in opposed relation with respect to each other, means for locking the arms in relatively separated position, said means being releasable to permit the ends of the arms to swing 15 toward each other by gravity, and means for downwardly actuating the rod to lower the arms so that upon upward movement of the rod and release of the locking means the arms will swing together toward each other and engage the lower 20 side edges of the rail head.

7. A device for clamping and supporting mobile units upon railway track rails, including a vertically movable rod, arms pivotally connected to each other and the rod in opposed relation with respect to each other, means for locking the arms in relatively separated position, said means being releasable to permit the ends of said arms to swing toward each other by gravity, rollers having a circumferential flange mounted at the lower 30 ends of the arms, and means for downwardly actuating the rod to lower said arms so that upon upward movement of the rod and release of the 35 said locking means, the arms will swing toward each other and engage the rollers with the lower side edges of the rail head.

8. A device for clamping and supporting mobile units upon railway track rails, including a vertically movable rod, means tending to resist downward movement of said rod, arms pivotally connected to each other and the rod in opposed relation with respect to each other, means for locking the arms in relatively separated position, said means being releasable to permit the ends of said arms to swing toward each other by gravity, rollers having a circumferential flange mounted at the lower ends of the arms, and means for downwardly actuating the rod to lower said arms so that upon upward movement of the rod and release of said locking means, the arms will swing 50 toward each other and engage the rollers with the lower side edges of the rail head.

9. A device for clamping and supporting mobile units upon railway track rails, including a casing, a rod movable axially within the casing, means tending to resist displacement of said rod with respect to the casing, a disk mounted at the lower end of the rod and movable therewith, a pin projecting laterally from said disk and extending through a slot in said casing, arms pivotally connected together in opposed relation to each other, links pivotally connecting the upper ends of said arms to the disk, roller members having a peripheral flange rotatably mounted at the lower ends of each of said arms, a locking device pivotally mounted upon the laterally projecting pin and engaging the common pivot of said arms to secure the same in separated relation, and means for actuating the rod to lower the arms so that upon upward movement of the rod and release of the locking means the arms will swing toward each 75

other and engage the rollers with the underside edges of the rail head.

10. A device for clamping and supporting mobile units upon railway track rails, including a casing, a rod movable axially within the casing, 5 means tending to resist displacement of said rod with respect to the casing, a disk mounted at the lower end of the rod and movable therewith, a pin projecting laterally from said disk and extending through a slot in said casing, arms pivotally connected together in opposed relation to each other, links pivotally connecting the upper ends of said arms to the disk, a locking device pivotally mounted upon the laterally projecting pin and engaging the common pivot of said arms 15 to secure the same in separated relation, and means for actuating the rod to lower the arms so that upon upward movement of the rod and release of the locking means the arms will swing toward each other and engage the rollers with 20 the underside edges of the rail head.

11. A device for clamping and supporting mobile units upon railway track rails, including a movable rod, a disk mounted at the lower end of the rod and movable therewith, a pin projecting 25 laterally from said disk, arms pivotally connected together in opposed relation to each other, links pivotally connecting the upper ends of said arms to the disk, a locking device pivotally mounted upon the laterally projecting pin and engaging 30 the common pivot of said arms to secure the same in separated relation, and means for actuating the rod to lower the arms so that upon upward movement of the rod and release of the locking means the arms will swing toward each other and 35 engage the rollers with the underside edges of the rail head.

12. A device for clamping and supporting mobile units upon railway track rails, including a casing, a rod movable axially within the casing, 40 means tending to resist displacement of said rod with respect to the casing, a disk mounted at the lower end of the rod and movable therewith, a pin projecting laterally from said disk and extending through a slot in said casing, arms 45 pivotally connected together in opposed relation to each other, links pivotally connecting the upper ends of said arms to the disk, roller members having a peripheral flange rotatably mounted at the lower ends of each of said arms, a locking device pivotally mounted upon the laterally projecting pin and engaging the common pivot of said arms to secure the same in separated relation, an arm for actuating the rod downwardly 50 against the compression of the spring to place the rollers at the lower ends of the pivotally opposed arms in a position relative to the head of the track rail whereby the arms may swing toward each other by gravity upon release of said locking device and engage the rollers at the 55 lower ends thereof with the lower side edges of said rail head.

13. A device for clamping and supporting mobile units upon railway track rails, including a vertically movable rod, arms pivotally connected 65 to each other and the rod in opposed relation with respect to each other, means for locking the arms in relatively separated position, said means being releasable to permit the ends of said arms to swing toward each other by gravity, members having a circumferential flange mounted at the lower ends of the arms, and means for downwardly actuating the rod to lower said arms so that upon upward movement of the rod and re- 70

lease of the said locking means, the arms will swing toward each other and engage the members with the lower side edges of the rail head, said members being rotatably mounted to permit the unit to be moved along the track without disengaging said members from the rail head.

14. In a machine adapted to be supported upon railway track rails, a mechanism for clamping the machine to a rail including a pair of clamp members pivotally mounted for movement to-

ward and away from each other, yielding means normally urging said members toward each other to clamp the rail therebetween, means for separating said members against the action of said yielding means, and means for raising said clamp members above rail clamping position and for lowering said members into clamping position while the said members are in relatively separated position.

HENRY J. PERAZZOLI. 10
